UNITED STATES PATENT OFFICE

EDWARD F. WILLIAMS, OF MEMPHIS, TENNESSEE

VANITY-CASE ACCESSORY CLAMP

Application filed August 15, 1929. Serial No. 386,103.

The present invention relates to an accessory clamp for vanity cases and is designed particularly for use by women, (when seated and exposed to air currents) in weighting down the hem of the dress when the vanity case is not otherwise in use. The object of thus weighting down the hem is to prevent it from being blown upward by air current, as while seated in a swiftly moving automobile.

However other uses are comprehended within the scope of this device.

Another very important object of the invention resides in the provision of a structure of this nature which is simple, inexpensive to manufacture, strong and durable, thoroughly efficient and reliable in use, easy to manipulate and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of the device,
Figure 2 is a side elevation,

Figure 3 is a sectional side elevation,

Figure 4 is a sectional view through the device showing the hinge means,

Figure 5 is a top plan view of the case,

Figure 6 is a plan view of the clamp plate,

Figure 7 is a perspective view of the pins and springs and

Figure 8 is a detail section through the hinge ears.

Referring to the drawing in detail it will be seen that the numeral 1 designates a piece of metal which will be referred to hereinafter as a clamp plate. This clamp plate 1 conforms in shape with the major portion of the vanity case 6. The clamp plate 1 is held firmly to the case 6 by means of a pin 8 passing through the eyes of hinge ears 2 and 7.

The pin 8 is expanded at the ends in such a manner as to prevent its slipping out. Clamp plate 1 is pressed firmly against the case proper by coiled springs 9 which press

against the outer surface of the case 6 and against the inner surface of the thumb lift 3 formed on the hinged edge of the plate 1.

The following parts are preferably integral with the clamp plate 1, the hinge ears 2 and the thumb lift 3 and the spring cover flanges 4.

These flanges 4 are at the hinged edge of the plate 1 and extend at right angles therefrom inwardly toward the case 6. Thus the major portion of the flange structure may be manufactured in one piece. The hinge ears 7 are integral with the case proper 6 and may be manufactured by punching them out of the case 6 at the sides of the top thereof and then bending them up to the vertical position.

Soft material such as felt 5 is caused to adhere (as by gluing) to the inner face of the clamp plate 1 and to the opposing surface 70 of the case 6 most nearly in contact with it.

When it is desired to clamp the case to an object, as the hem of the dress the thumb is pressed against the thumb lift 3—3 which is at an obtuse angle (slightly less than a straight angle) to the clamp plate 1—1 and the fingers are pressed against the opposite (bottom if the clamp side is fitted at the top) surface of the case proper 6.

The hem, for example, is then allowed to fall into between the soft materials 5. The thumb then allows the clamp to close. Exactly similar means are used to disengage the clamp, the hem, for example, being withdrawn instead of inserted.

The spring cover flanges 4 serve to protect the springs from dust and coming into contact with objects which they might tear or otherwise injure.

The advantages of the vanity case accessory clamp are as follows:

It serves as a means of attachment of the case to some portion of the wearing apparel while seated, for example, so that on moving about as in rising from a seat, it will not be accidentally dropped and broken or forgotten and lost.

A practical illustration of this is as follows:

Many women go to the theater and lay the case unattached on their apparel simply be-

cause there is no other simple disposition that can be made of it. On rising they frequently forget about the case and spill it, thus breaking it. Another illustration is this: Under the same circumstances other women lay the case down on the next seat and later forget it on leaving the theater. If the case were attached to the wearing apparel it would not be lost even if forgotten.

10 The case with this attachment can be used to attach the case to the belt, for example, while walking or standing and thus save the inconvenience of carrying the article in the hand.

15 The invention can be used to attach thin articles as a handkerchief, to the vanity case. This is a convenient means of keeping them together while holding them in the hand or even when placed elsewhere.

20 The invention prevents the usual embarrassment to women whose apparel of light textile fabric is frequently liable to be blown upwardly by air currents, whether natural or artificial. This function is performed 25 simply by weighting down the fabric at the point most vulnerable to the effect of the wind.

It is simple to operate and, in fact, offers little, if any, inconvenience, such as would 30 result from carrying a piece of apparatus which serves no other purpose. It increases the bulk of the case only to a slight degree.

The invention does no harm to fabric or 35 wearing material, unless the latter is much more fragile than the average. The soft padded material, such as felt, is used to protect the fabric of the wearing apparel from injury, as would result in case an entirely metal clamp were employed.

40 It is thought that the construction, operation, utility and advantages of this invention will now be quite apparent to those skilled in this art without a more detailed description thereof.

45 It is apparent that changes in the details of construction, and in the combination and arrangement of parts may be resorted to without departing from the spirit or scope of the invention as hereinafter claimed or sacrificing 50 any of its advantages.

Having thus described my invention, what I claim as new is:

1. In combination, a vanity case, a clamp plate, means for hingedly mounting the clamp plate on one surface of the case, and means normally urging the plate toward said surface, an obtuse extension from the hinged edge of the plate forming a thumb lift.

60 2. In combination, a vanity case providing a pair of apertured ears, a clamp plate having a pair of opposite apertured ears, a pin extending through the apertured ears to hingedly mount the plate on the case, spring 65 means on the pin associated with the plate

on the case to hold the plate normally toward the case.

3. In combination, a vanity case providing a pair of apertured ears, a clamp plate having a pair of opposite apertured ears, a pin extending through the apertured ears to hingedly mount the plate on the case, spring 70 means on the pin associated with the plate on the case to hold the plate normally toward the case, flanges on the hinged edge of the 75 plate to protect the spring means.

4. In combination, a vanity case providing a pair of apertured ears, a clamp plate having a pair of opposite apertured ears, a pin extending through the apertured ears to 80 hingedly mount the plate on the case, spring means on the pin associated with the plate on the case to hold the plate normally toward the case, flanges on the hinged edge of the 85 plate to protect the spring means, an obtuse thumb lift extending from the hinged edge of the plate.

5. In combination, a vanity case providing a pair of apertured ears, a clamp plate having a pair of opposite apertured ears, a pin 90 extending through the apertured ears to hingedly mount the plate on the case, spring means on the pin associated with the plate on the case to hold the plate normally toward the case, flanges on the hinged edge of 95 the plate to protect the spring means, an obtuse thumb lift extending from the hinged edge of the plate, soft material on said surface of the case and on the opposed surface of the plate.

In testimony whereof I affix my signature.
EDWARD F. WILLIAMS.
